EXPANSION JOINT FOR CONCRETE
PAVEMENTS

James T. Hallett, Indianapolis, Ind.

Application February 13, 1937, Serial No. 125,529

11 Claims.

(Cl. 94—18)

The present application relates to expansion joints for concrete pavements, and the like. The primary object of my invention is to improve the structure and operation of joints of the prior art, by providing an improved load-transfer element. Further objects of the invention will appear as the description proceeds.

To the accomplishment of the above and related objects, my invention may be embodied in the form illustrated in the accompanying drawing, attention being called to the fact, however, that the drawing is illustrative only, and that change may be made in the specific construction illustrated and described, so long as the scope of the appended claims is not violated.

In said drawing, Fig. 1 is a vertical section through a joint constructed in accordance with my invention, the plane of the figure extending longitudinally of the roadway;

Fig. 2 is a fragmental plan view of a load-transfer element constructed in accordance with my invention; and

Fig. 3 is a fragmental elevation of the metal plate forming a part of the organization of my invention.

Referring more particularly to the drawing, it will be seen that the reference numerals 1 and 2 indicate the end portions of adjacent blocks of a concrete pavement. Interposed between said blocks is a metal plate 3, from the body of which has been punched a series of tongues 4 which project downwardly and outwardly from one surface of the plate 3. It will be clear that all of the tongues 4 of this series lie substantially in a common plane; and, as is shown in Fig. 1, the free ends of those tongues are curled upwardly as at 5. Preferably, the ends of all of the tongues 4 of this series are curled substantially about a common axis.

A second series of tongues 6 is punched out of the body of the plate 3, and these tongues project upwardly and outwardly from the opposite face of the plate 3. The tongues 6 of the second series lie substantially in a common plane, and their free ends are downwardly curled as at 7, preferably substantially about a common axis.

In order to permit expansion of the concrete blocks, I interpose between the faces of the plate 3 and the adjacent blocks 1 and 2, layers 50 of suitable plastic or compressible material, such as is familiar to those acquainted with this art. Preferably, these layers of material are preliminarily secured to the plate faces. In the illustrated embodiment of my invention, a layer 55 8 of such material is applied to that face of the

plate 3 from which project the tongues 6, said layer extending from the upper edge 9 of the plate toward the lower edge 10 thereof to a line near that from which the tongues 6 spring. A second layer 11 of such material is applied to the opposite face of the plate, extending from the lower edge 10 of the plate toward the upper edge 9 thereof to a line near that from which the tongues 4 spring. Obviously, both layers will extend from end to end of the plate 3; and, since they overlap, as is clearly shown in Fig. 1, they cooperate to close the openings 12 formed in the body of the plate by punching out the tongues 4 and 6.

In use, the plate 3, with the layers 8 and 11, 15 is positioned on the foundation 16 for the pavement before the blocks 1 and 2 are poured. Obviously, as the concrete blocks are poured, the tongues 4 are solidly embedded in the block 1, while the tongues 6 are solidly embedded in the block 2. Preferably, the upper adjacent edges of the two blocks will be shaped, as shown, to provide a groove which is preferably partially filled, in accordance with standard practice, with a suitable plastic filler as at 13.

It will be clear that, after the blocks 1 and 2 have set and hardened, a load applied to the block 1 will place the tongues 4 in tension, whereby the plate 3, intermediate the tongues 4 and 6, will be placed in compression, said plate 30 being of sufficient vertical rigidity to transmit the load, by placing the tongues 6 in tension, to the block 2. Conversely, a load applied to the block 2 will place the tongues 6 in compression, whereby the plate 3, intermediate the tongues 4 and 6, will be placed in tension to transmit the load, by placing the tongues 4 in compression, to the block 1.

If desired, a metal rod 14 may be associated with the curled ends 5 of the tongues 4 of one series, and a metal rod 15 may be associated with the curled ends 7 of the tongues 6 of the other series. This arrangement somewhat stiffens the assembly and tends to distribute loads uniformly throughout the whole of either 45 series. While I consider such an arrangement to have certain advantages, I do not consider it as an essential to the successful practice of my invention.

Obviously, as a wheeled vehicle approaches, 50 crosses, and then leaves the joint of my invention, the two series of tongues and the plate body are placed in alternate tension and compression, whereby maximum use is made of the strength of the metal. I consider the joint of 55

my invention to be applicable only to joints of small dimensions, and believe that it will function satisfactorily only if total relative movement of the adjacent ends of blocks 1 and 2 is one-eighth of an inch or less; and therefore I believe that successive joints should be spaced from each other not more than approximately ten feet.

It will be clear, from a consideration of the disclosure of the present application that, contrary to ordinary practice the load transfer portion of the joint of the present application adjusts itself to expansion, contraction, and curling conditions of the pavement slabs by flexing of the tongues 4 and/or 6. The advantages flowing from such an arrangement, as compared with previously known arrangements in which there is a sliding engagement between elements of the load transfer device, will be entirely obvious.

I claim as my invention:

1. An expansion joint element for use between adjacent poured blocks of concrete pavements, and the like, comprising a relatively rigid metal plate capable of taking vertical compression and adapted to be positioned on edge between such adjacent blocks, said plate being formed, adjacent its upper edge, with a plurality of tongues, punched out of the body of the plate and projecting downwardly and outwardly from one face of the plate and adapted to be embedded in one of said blocks, and, adjacent its lower edge, with a plurality of tongues, punched out of the body of the plate and projecting upwardly and outwardly from the other face of said plate and adapted to be embedded in the other of said blocks, a layer of compressible material associated with the first-mentioned face of said plate and extending from the lower edge thereof toward the upper edge, and a layer of compressible material associated with the second-mentioned face of said plate and extending from the upper edge thereof toward the lower edge, said layers overlapping to close the openings formed by punching out said tongues.

2. An expansion joint for concrete pavements and the like, comprising two adjacent pavement blocks, a metal plate disposed between said blocks, and means carried by said plate and embedded in said respective blocks for transmitting load strains from one of said blocks to the other, said means being placed in tension and said plate in compression to transmit load from one of said blocks to the other, and said means being placed in compression and said plate in tension to transmit load from said other block to said one block.

3. An expansion joint for concrete pavements and the like, comprising two adjacent pavement blocks, a substantially vertically rigid metal plate disposed between said blocks, a series of tongues projecting downwardly and outwardly from one face of said plate, disposed substantially in a common plane, and embedded in one of said blocks, and a series of tongues projecting upwardly and outwardly from the other face of said plate, disposed substantially in another common plane, and embedded in the other of said blocks.

4. An expansion joint for concrete pavements and the like, comprising two adjacent pavement blocks, a metal plate disposed on edge between said blocks and extending transversely substantially the full width of said blocks, said plate being relatively rigid to take and transmit substantially vertical compressive loads, a series of

tongues projecting downwardly and outwardly from one face of said plate, disposed substantially in a common plane, and embedded in one of said blocks, and a series of tongues projecting upwardly and outwardly from the other face of said plate, disposed substantially in another common plane, and embedded in the other of said blocks, the free ends of said first series of tongues being upwardly curled, and the free ends of said second series of tongues being downwardly curled.

5. A load-transfer expansion joint unit for use between adjacent poured blocks of concrete pavements, and the like, comprising a relatively rigid metal plate capable of taking compression in the direction of its vertical dimension and adapted to be positioned on edge between such adjacent blocks and presenting to each of said blocks a single plane surface extending from its top edge to its bottom edge, said plate being formed, adjacent its upper edge, with a plurality of tongues projecting downwardly and outwardly from its one face and adapted to be embedded in one of said blocks, and, adjacent its lower edge with a plurality of tongues projecting upwardly and outwardly from its other face and adapted to be embedded in the other of said blocks.

6. A load-transfer expansion joint unit for use between adjacent poured blocks of concrete pavements, and the like, comprising a relatively rigid metal plate capable of taking compression in the direction of its vertical dimension and adapted to be positioned on edge between such adjacent blocks and presenting to each of said blocks a single plane surface extending from its top edge to its bottom edge, said plate being formed, adjacent its upper edge, with a plurality of tongues bent from the plane of said plate about a horizontal axis and projecting downwardly and outwardly from its one face and adapted to be embedded in one of said blocks, and, adjacent its lower edge with a plurality of tongues bent from the plane of said plate about a horizontal axis and projecting upwardly and outwardly from its other face and adapted to be embedded in the other of said blocks.

7. A load-transfer expansion joint unit for use between adjacent poured blocks of concrete pavements, and the like, comprising a relatively rigid metal plate capable of taking compression in the direction of its vertical dimension and adapted to be positioned on edge between such adjacent blocks and presenting to each of said blocks a single plane surface extending from its top edge to its bottom edge, said plate being formed, adjacent its upper edge, with a plurality of tongues lying in a common plane angularly related to the plane of said plate and projecting downwardly and outwardly from its one face and adapted to be embedded in one of said blocks, and, adjacent its lower edge with a plurality of tongues lying in another common plane angularly related to the plane of said plate and projecting upwardly and outwardly from its other face and adapted to be embedded in the other of said blocks.

8. A load-transfer expansion joint unit for use between adjacent poured blocks of concrete pavements, and the like, comprising a relatively rigid metal plate capable of taking compression in the direction of its vertical dimension and adapted to be positioned on edge between such adjacent blocks and presenting to each of said blocks a single plane surface extending from its top edge to its bottom edge, said plate being formed, adjacent its upper edge, with a plurality of tongues

spaced longitudinally of said plate and projecting downwardly and outwardly from its one face and adapted to be embedded in one of said blocks, and, adjacent its lower edge with a plurality of 5 tongues spaced longitudinally of said plate and projecting upwardly and outwardly from its other face and adapted to be embedded in the other of said blocks.

9. A load-transfer expansion joint unit for use 10 between adjacent poured blocks of concrete pavements, and the like, comprising a metal plate positioned on edge between such adjacent blocks, said plate being relatively rigid vertically to bear and transmit compressive substantially vertical 15 loads, and said plate being provided with anchorage elements in two series, one series of anchorage elements being secured to said plate adjacent the upper edge thereof and inclining downwardly and outwardly therefrom and embedded in one 20 of said blocks, and the other series being secured to said plate adjacent the lower edge thereof and inclining upwardly and outwardly therefrom and embedded in the other of said blocks.

10. A load-transfer expansion joint unit for use 25 between adjacent poured blocks of concrete pavements, and the like, comprising a metal plate positioned on edge between such adjacent blocks, said plate being relatively rigid vertically to bear and transmit compressive substantially vertical

loads, and said plate being provided with anchorage elements in two series, one series of anchorage elements being secured to said plate adjacent the upper edge thereof and inclining downwardly and outwardly therefrom and embedded in one 5 of said blocks, and the other series being secured to said plate adjacent the lower edge thereof and inclining upwardly and outwardly therefrom and embedded in the other of said blocks, said plate being free from attachment to said blocks between 10 said two series of elements.

11. A load-transfer joint comprising a metallic strip extending transversely of a pavement between longitudinally adjacent pavement blocks and presenting uninterrupted plane surfaces to 15 said respective blocks, said strip being provided with a plurality of fins projecting from a level adjacent the upper surface of the pavement downwardly and outwardly and embedded in one of said blocks, and with a plurality of fins project- 20 ing from a level adjacent the lower surface of the pavement upwardly and outwardly and embedded in the other of said blocks, said fins having a substantial horizontal dimension, means liberating at least the lower half of said strip from 25 said first-named block, and means liberating at least the upper half of said strip from said last-mentioned block.
